UNITED STATES PATENT OFFICE.

DAVID G. HUSSEY, OF NANTUCKET, MASSACHUSETTS.

IMPROVEMENT IN HORSE-RAKES.

Specification forming part of Letters Patent No. 38,965, dated June 23, 1863.

To all whom it may concern:

Be it known that I, DAVID G. HUSSEY, of Nantucket, in the county of Nantucket and State of Massachusetts, have invented a new and Improved Horse Hay-Rake; and I do hereby declare that the following is a full, clear, and exact description of the same, reference being had to the accompanying drawings, making a part of this specification, in which—

Figure 1 is a side sectional view of my invention, taken in the line *x x*, Fig. 2. Fig. 2 is a plan or top view of the same; Fig. 3, an enlarged longitudinal section of a portion of the rake-head, taken in the line *y y*, Fig. 1.

Similar letters of reference indicate corresponding parts in the several figures.

To enable those skilled in the art to fully understand and construct my invention, I will proceed to describe it.

A represents a platform, to each side of which a thill, *B*, is permanently attached, and *C* is the driver's seat, which is secured on the upper end of an elastic support, *D*, the latter being attached to the platform *A*. The thills *B B* extend a short distance beyond the back end of the platform *A* sufficiently so to admit of them being attached by clamps *a a* to axle *E* of the wheels *F F*, which support the back end of the machine.

I represents a frame, which is composed of two parallel bars, *c c*, connected by two cross-rods, *d*. The back part of this frame *I* is fitted on a rod, *e*, which is placed in pendants *f* at the back part of the platform *A*, and is allowed to swing freely on said rod *e*. The bars *c c* have each an upright bar, *g*, attached to them, and these bars *c* pass up through guides *h*, which are secured to the outer sides of the thills *B B*. The bars *c* are perforated with holes to admit of pins *i* passing through them, and by adjusting these pins in different holes in the bars *g* the frame *I* may be retained at a greater or less degree of inclination, as may be desired. (See Fig. 1, in which said frame is shown in two positions, one in black and the other in red.)

In the front part of the frame *I* there is fitted a tubular shaft, *J*. This shaft is placed

in bearings *h' h'* at the front end of the bars *c c*, and it has two arms, *i' i'*, attached to it at right angles. These arms *i' i'* have each a perforated sector, *j*, at their ends to which rods *k* are connected by pins *l*. The back ends of the rods are connected by pins *m* to arms *n n* on a shaft, *o*, in the frame *I*, said shaft having a lever, *K*, attached to it, which lever extends up through a slot in the platform *A*, having a notched plate, *p*, at one side of it, by which the lever *K* may be held at different points within the scope of its movement.

To the under side of the tubular shaft *J* there are attached longitudinally a series of small tubes, *g*, in which rods *r* are fitted and allowed to turn freely. These rods *r* have curved wire teeth *L* attached to them, the form of which is shown clearly in Fig. 1. It will be seen, by referring to this figure, that the teeth extend over the shaft *J*, and that by turning said shaft, which may be done by operating the lever *K*, the teeth may be raised and lowered, and the teeth are thus raised in order to discharge their load. In Fig. 1 this elevated position of the teeth is indicated in blue outline.

The teeth *L* may be adjusted higher or lower by raising or lowering the front end of the frame *I*, as previously described, and by this arrangement of said frame it will be seen that the thills *B* may be attached to an axle having wheels of greater or less diameter, the adjustment of the frame *I* admitting of this. Hence a farmer may use the wheels and axle of any ordinary wagon or agricultural implement. On the front cross-rod, *I*, of the frame *I* there are placed loosely two arms, *t t*, to the front ends of which a rod, *u*, is attached. This rod *u* extends over the teeth *L* of the rake-head which are between the thills *B B*, and said rod *u* has a treadle-frame *M* attached to it, which extends upward within the reach of the feet of the driver, who, by pressing down the frame *M* at any time, will cause the rod *u* to bear upon the teeth *L* underneath it and hold said teeth down. This arrangement admits of the bunching of the hay in windrows. The teeth *L* are allowed to rise and fall freely, and independently of

each other, so that they may conform to the inequalities of the ground over which they pass.

Having thus described my invention, what I claim as new, and desire to secure by Letters Patent, is—

The attaching of the teeth L to the shaft or rake-head J by means of the rods r, fitted

loosely in tubes q, which are secured to the shaft or rake-head, substantially as and for the purpose set forth.

DAVID G. HUSSEY.
